CYRUS HANKINS, OF BALTIMORE, MARYLAND, ASSIGNOR, BY MESNE ASSIGNMENTS,
TO T. H. SYMINGTON AND SON, INC., OF BALTIMORE, MARYLAND, A CORPORATION
OF MARYLAND

RAILWAY-CAR-TRUCK SPRING

Application filed June 13, 1925. Serial No. 36,976.

The invention relates to spring devices for use in connection with railway car trucks.

The principal object of the invention, generally stated, is to provide a spring device adapted for mounting within the window opening of a truck side frame and including casing or housing sections confining and substantially enclosing the cushioning means or spring device.

10 The object of the invention, more specifically stated, is to provide a truck spring device embodying casing sections enclosing cushioning means including or consisting of banks or groups of concentric plate springs, 15 means being provided for restricting movement of the springs in all planes at an angle to the line of load.

Another object of the invention is to provide a structure of this character in which 20 the casing sections are equipped with means directly engaged by the cushioning means and acting to take up any wear caused by chafing, the casing sections themselves being consequently relieved of such wear.

25 A further object of the invention is to provide wear take-up means which will act also to retain the cushioning means in proper operative position within and between the casing sections whereby displacement or 30 location of the cushioning elements in any direction other than in the line of load will be prevented.

A still further object of the invention is the provision of a spring device in which the 35 wear take-up members or means will act also as guides during movement of the casing sections toward each other under compression, the wear take-up members being connected with and carried by the casing sections 40 so as to move therewith, the connection being, moreover, one avoiding the employment of auxiliary securing elements, the cushioning means coacting with the wear take-up members to retain them in place.

45 Yet another object of the invention is the provision of a device of this character in which the wear take-up means also constitutes spacing means for the sets of springs constituting the cushioning means, the successive sets being consequently maintained

out of engagement so that friction will be reduced.

To the attainment of the foregoing and other objects and advantages such as simplicity, cheapness in manufacture, ease of 55 assembling and convenience in installation the invention may consist in the details of construction and the combination and arrangement of parts to be hereinafter more fully described and claimed and illustrated 60 in the accompanying drawings wherein like characters of reference designate corresponding parts throughout the several views.

In the drawings:

Figure 1 is a side elevation of a railway truck frame showing the spring device in place, 65

Figure 2 is a longitudinal vertical section taken through the complete assembled device on substantially the line 2—2 of Figure 3, 70

Figure 3 is a central cross section therethrough, the view being taken on substantially the line 3—3 of Figure 2,

Figure 4 is a horizontal section taken on the line 4—4 of Figure 3, and 75

Figure 5 is a detail perspective view showing coacting groups of the combined wear receiving, guiding and spring spacing means.

Referring more particularly to the drawings I have illustrated a portion of a railway car truck including the usual frame 1 having a window opening 2 therein within which is located my spring device designated generally by the numeral 3, this spring device being interposed between the spring seat 4 and the bolster 5, 80

In carrying out the invention I provide a sectional casing or housing including upper and lower similar pans or casing sections 6 having peripheral flanges 7 and arranged in vertical spaced relation with their flanges extending toward each other. The casing defined by these sections contains and substantially encloses the cushioning means which preferably consists of sets of concentric elongated plate springs 8 arranged in superposed groups or banks in any desired manner. If preferred, the arrangement may be such as that disclosed in my co-pending application filed June 13, 1925, Serial No. 36,978 85

though there is no limitation in this respect as the number of sets, the number of groups or banks in a set, the number of plates in a group or bank and the arrangement and relative positions thereof may be varied within wide limits.

To maintain the cushioning means in proper position between the casing sections and to restrict their movement to the line of load I preferably provide a plurality of combined wear, guide and spacing members indicated generally at 9 and 10, these members being located within the end portions of the pans or casing sections and arranged in groups, the number in a group depending upon the number of sets of springs employed. Each member 9 is shown as comprising a substantially U-shaped body including a plate portion 11 and arm portions 12 and 13, all of which preferably have their upper edges flush. The lower edge of the plate portion 11 is inclined as indicated at 14 and the lower edges of the arm portions 12 and 13 are oppositely inclined as shown at 15 and 16. As three sets of springs are illustrated I make use of three of the members 9 arranged side by side and located within each end of the upper pan or casing section, the plate portions 11 bearing against the inner faces of the end flanges, and the arm portion 12 of one endmost member bearing against or located adjacent the inner face of one side flange. The arm portion 13 of the other endmost one of the group is disposed adjacent the inner face of the opposite side flange. This arrangement is well illustrated in Figure 3. The other arm portions 12 and 13 are located adjacent each other and may be in contact if such is found desirable for any reason. The members 9 are of sufficient length that the ends of the plate portions 11 and arms 12 will extend below the upper edge of the lower pan or casing section when the two casing sections are in their outermost or most widely separated position.

Each of the members 10 may be formed as a U-shaped body including a plate portion 17 and arm portions 18 and 19 all of which have their lower edges flush or in the same plane. The upper edge 20 of the plate portion 17 is inclined corresponding to the inclination of the edge 14 of the plate portion 11 of the member 9 so as to be parallel therewith, and the upper edges 21 and 22 of the arm portions 18 and 19 are inclined at the same angle as the edges 15 and 16 of the member 9 located thereabove. The number of members 10 corresponds to the number of members 9 and they are located therebelow. The length of the plate portions 17 and arm portions 19 is such that they will project upwardly beyond the lower edge of the upper pan or casing section.

These members 9 and 10 are located within the upper and lower pans, respectively,

and are held thereto as for instance by means of outstruck lugs 23 and 24 formed, respectively, on the plate portions 11 and 17, these lugs passing through suitable slots 25 formed in the flanges 7 of the upper and lower pans or casing sections. By this particular mounting it is evident that the employment of bolts, rivets or other auxiliary securing elements is avoided.

When the casing sections are assembled with the members 9 and 10 in place, these members 9 and 10 define pockets within which the end portions of the sets of springs engage so that the successive sets will be held in spaced relation to one another and out of contact with the pans or casing sections. This brings all the wear, caused by chafing, on the members 9 and 10 except at those points where the springs engage the top and bottom of the respective pans. The spacing apart of the sets of springs greatly reduces friction between the sets. Owing to the fact that the upper members 9 project into the lower pan or casing section and that the members 10 project into the upper pan or casing section, it is clear that there is never an obstructed space between the casing sections permitting lateral displacement of any of the individual elements in the groups or banks of springs. Obviously this will prevent movement in all planes at an angle to the line of load, the movement being thus entirely confined to the vertical. The members 9 and 10 coact to constitute guides not only for the springs but also for the casing sections as they move together under compression or apart under release. As the confronting inclined edges of the upper and lower members 9 and 10 are parallel there can never be any interference with the proper movement of any of the parts.

From the foregoing description and a study of the drawings it will be seen that I have thus provided an easily constructed and assembled spring device which on account of the structural features above set forth and the characteristics resulting therefrom will be highly efficient and satisfactory in use and also durable in service especially as the arrangement and combination are such that dislocation or likelihood of destruction from wear and other causes will be reduced to the minimum.

While I have shown and described a preferred embodiment of the invention, it should be understood that the exact details are merely illustrative as various modifications and changes may be made within the spirit of the invention and without departing from the scope of the appended claims.

Having thus described the invention, I claim:

1. In a railway car truck spring device, a pair of casing sections of pan-like formation arranged with their open sides toward each

other and normally spaced apart, sets of cushioning devices located within and between the casing sections, and means detachably mounted within said sections for spacing the adjacent sets laterally apart.

5. 2. In a railway car truck spring device, a pair of casing sections of pan-like formation arranged with their open sides toward each other and normally spaced apart, sets of cushioning devices arranged side by side located within and between the casing sections, and means engaging against outer sides of the cushioning devices for spacing the adjacent sets apart and spacing the outermost sets 10 from the sides of the casing sections.

15. 3. In a railway car truck spring device, a pair of casing sections of pan-like formation arranged with their open sides toward each other and normally spaced apart, sets of cushioning devices located within and between the casing sections, and means spacing the adjacent sets apart, said means in each casing section extending into the other for preventing movement of the cushioning 20 means in all planes at an angle to the line of load.

25. 4. In a railway car truck spring device, upper and lower members, a plurality of sets of concentric plate springs interposed between said members, and means carried by said members and forming pockets within which the ends of the sets of springs are engaged.

30. 5. In a railway car truck spring device, upper and lower main members, a plurality of sets of springs arranged side by side between said members, and means carried by said main members and extending toward each other in overlapping spaced relation defining 35 pockets receiving the springs for maintaining them in spaced relation and preventing lateral movement thereof.

40. 6. In a railway truck spring device, upper and lower members, a plurality of sets of 45 elongated plate springs interposed between said members, and spacing members carried by the upper and lower members and arranged in spaced overlapping relation, said spacing members including arm portions located between the sets of springs.

45. 7. In a railway truck spring device, upper and lower casing sections having flanges extending toward each other, the flanges being formed with slots, a plurality of sets of elongated plate springs interposed between the 50 casing sections, and groups of angular members mounted within the upper and lower casing sections and having lugs passing through said slots, said angular members 55 having portions located between the sets of springs for maintaining the same in spaced relation.

60. 8. In a railway truck spring device, upper and lower casing sections having flanges extending toward each other, the flanges being

formed with slots, a plurality of sets of elongated plate springs interposed between the casing sections, and groups of angular members mounted within the upper and lower casing sections and having lugs passing through said slots, said angular members having portions located between the sets of springs for maintaining the same in spaced relation, the angular members in each casing section extending into the other.

70. 9. In a railway truck spring device, upper and lower casing sections having flanges extending toward each other, the flanges being formed with slots, a plurality of sets of elongated plate springs interposed between the casing sections, and groups of angular members mounted within the upper and lower casing sections and having lugs passing through said slots, said angular members having portions located between the sets of springs for maintaining the same in spaced relation, the angular members in each casing section extending into the other, the confronting edges of the upper and lower angular members being inclined, parallel and spaced to permit movement of the casing sections toward each other.

75. 10. In a railway truck spring device, upper and lower casing sections, elongated concentric plate spring interposed between said sections, and substantially U-shaped members mounted within the casing sections and embracingly engaging said springs, said members having spaced overlapping portions.

80. 11. In a spring structure, spaced casing sections having flanges, pocket forming members located within the sections and detachably connected with the flanges thereof, and cushioning means located within the pocket forming members.

85. 12. In a spring structure, upper and lower spaced casing sections, laterally arranged pocket forming members located within the sections, and cushioning means arranged between the sections and including a plurality of sets of superposed plate springs having their end portions embracingly engaged within said pocket forming members.

90. 13. In a spring structure, spaced casing sections, pocket forming members mounted therein and detachably directly connected thereto, and a plurality of sets of superposed plate springs arranged between the sections with their end portions engaged within said pocket forming members.

95. 14. In a railway truck spring structure, spaced casing sections, a plurality of angular pocket forming members located within the casing sections, means for holding the pocket forming members anchored to the sections for movement therewith, and superposed plate springs engaged within and confined by said pocket forming members.

100. 15. In a spring structure, spaced casing sections, pocket forming members removably

mounted within the sections, and a plurality of banks of plate springs located between the sections with the banks arranged side by side, and the respective banks being engaged within corresponding pocket forming members.

5 16. In a spring structure, spaced casing sections, cushion members located between the sections and spacing and guide members detachably mounted within the casing sections and embracingly engaging said cushion members, said spacing and guide members being arranged side by side in contacting relation.

10 In testimony whereof I affix my signature.
